UNITED STATES PATENT OFFICE.

ROBERT T. REID AND JAMES L. McDONNELL, OF TACOMA, WASHINGTON,
ASSIGNORS OF ONE-HALF TO FRANK C. CARDIN AND JOHN T. BIBB, OF
SAME PLACE.

TELEPHONE SYSTEM.

SPECIFICATION forming part of Letters Patent No. 598,183, dated February 1, 1898.

Application filed May 7, 1897. Serial No. 635,528. (No model.)

To all whom it may concern:

Be it known that we, ROBERT T. REID and JAMES L. McDONNELL, of Tacoma, in the county of Pierce and State of Washington, 5 have invented certain new and useful Improvements in Telephone Systems; and we do hereby declare the following to be a full, clear, and exact description of the invention, such as will enable others skilled in the art to 10 to which it appertains to make and use the same.

Our invention relates to an improvement in telephone systems, the object of the invention being to increase the efficiency of party-lines on which a series of subscriber's-telephone apparatus is placed by the provision 15 of simple and efficient means whereby to render it impossible for a subscriber on such party-line to "cut in" his telephone while the line is being used by another subscriber, and 20 thus prevent one subscriber from interrupting or overhearing the conversation of another subscriber.

A further object is to provide a subscriber's-telephone apparatus with means whereby to 25 denote whether or not the line is in use.

With these objects in view the invention consists in certain novel features of construction and combinations and arrangements of parts, as hereinafter set forth, and pointed 30 out in the claims.

In the accompanying drawings, Figure 1 is a diagrammatical view illustrating our invention. Fig. 2 shows, theoretically, the connections made at the central office between 35 two party-lines to enable a subscriber on one of them to converse with a subscriber on the other. Fig. 3 is a detail view of the signaling or indicating device used in connection with a subscriber's instrument for notifying 40 the subscriber of the condition of the line. Fig. 4 is a modification of the signaling device.

A B represent the main conductors of a party-line, in circuit with which at the central office a battery 1, an annunciator 2, and 45 a resistance 3 are included. Subscribers' telephones and our improved "lock-out" devices are arranged in parallel between the main conductors. Any desired number of such sets of subscribers' apparatus may be em-

ployed on each party-line. In Fig. 1 of the 50 drawings four sets of subscribers' apparatus are shown, and each set is a duplicate of the others. A detailed description of one set will therefore suffice for all.

C represents the subscriber's transmitter, 55 D the hand-phone, E the switch-arm on which the hand-phone hangs, said switch-arm being connected with the line-wire A by means of a conductor a, and F represents the contact-screw with which the switch-arm engages 60 after the hand-phone has been removed therefrom, all of these devices being arranged in series in a multiple-arc circuit between the line conductors A B.

The switch-arm E is pivotally supported at 65 or near its center and a spring 4 tends to cause the hooked end thereof to approach the contact pin or screw F to close the telephone-circuit, said switch-arm being normally maintained removed from the contact pin or screw 70 by means of the weight of the hand-phone. The inner end of the switch-arm is beveled, as at 5, and terminates immediately over a beveled tooth or projection 6 at the upper end of a lever 7. The lever 7 is pivotally supported near its lower end and is maintained in its normal position with the tooth 6 under the end of the switch-arm by means of a spring 75 8. Adjustable stops 9 10 are provided to limit the movements of the lever 7. An elec- 80 tromagnet 12 is disposed near the lever 7 and adapted to attract an armature 11, carried by said lever. The coil or helix of the magnet 12 is of high resistance as compared with the multiple-arc telephone-circuit and forms part 85 of a normally open circuit, including the lever 7, switch-arm E, and conductor a.

From the construction and arrangement of parts above described it will be seen that when the hand-phone of one subscriber's-telephone apparatus (say at subscribers' station No. 1) is removed the hooked end of the switch-arm will commence to move toward the screw F; but its actual contact at this time with said screw will be prevented by engagement with the lever 7. As soon as this occurs a circuit, including the magnet 12, lines A B, battery 1, resistance 3, and an-

nunciator 2, will be closed. The magnet 12 will now attract its armature and thus move the toothed end of lever 7 out of the path of the beveled end of switch-arm E, whereupon 5 the latter will be permitted to complete its movement and making contact with the screw F close the multiple-arc circuit, which includes the subscriber's telephone, and thus put the subscriber in communication with the 10 central office, who will know from the dropping of annunciator 2 that he has called. Should now another subscriber (say at subscriber's station No. 2) remove his hand-phone from the switch-arm, the latter would turn 15 on its fulcrum and engage the coöperating lever 7 and close the circuit which includes the magnet 12 of the apparatus at subscriber's station No. 2. The coil of said magnet 12 is, as above explained, of high resistance— 20 much higher, in fact, than the resistance of the multiple-arc telephone-circuit—and consequently when any one of the telephone-circuits is closed all the magnets 12 will in effect be shunted, so that should a subscriber 25 at station No. 2 (or at any other station except the one at which the telephone is in use) remove his hand-phone from the switch-arm the circuit of the coöperating magnet 12 would be closed; but this circuit would not receive 30 enough current to energize the magnet sufficiently to result in the withdrawal of lever 7 from the path of the switch-lever, and this result will be further insured by the use of the resistance 3. The switch-arm E at station 35 No. 2 will thus be prevented from moving far enough to close its coöperating telephone-circuit while the telephone-circuit at station No. 1 (or at any other station) is closed.

It is desirable that some means be provided 40 whereby a subscriber may be notified when he desires to use the line whether or not the line is in use by another subscriber. For this purpose a bell 14 may be employed and adapted to be struck by a hammer 15 at the 45 free end of a spring-arm 16, secured to the switch-arm of each subscriber's-telephone apparatus. The bell will be so disposed with respect to the hammer that it will not be struck by the latter unless the switch-arm be 50 permitted to move to the full extent of its throw and make contact with the screw F. Thus it will be seen that if the bell be sounded when a subscriber removes his hand-phone the subscriber will be notified that the line 55 is not in use and that his call has been indicated at the central office.

It is evident that the signal for denoting 60 the condition of the line may be arranged to be operated electrically instead of mechanically when a subscriber removes his hand-phone from its hook. For instance, the arrangement shown in Fig. 6 may be adopted. In this form of the invention a magnet 17 is included in the telephone-circuit of each subscriber's apparatus and adapted to actuate a bell-hammer 18, arranged to strike a bell 19.

It is apparent that with this arrangement when the hand-phone has been removed and the switch-arm E has moved far enough to close the telephone-circuit the magnet 17 will 70 be energized and the bell sounded.

As before mentioned, it is desirable to employ a resistance, such as indicated at 3, to assist in insuring the practical inactivity of the magnets 12 when one of the multiple-arc 75 telephone-circuits is closed. If desired, however, a separate resistance might be omitted by making the coil of the annunciator-magnet of high resistance.

Should two subscribers on the same party-line desire to converse, their telephones may be included in circuit with each other by cutting out the resistance 3 at the central office or by increasing the battery-power, or both, and this can be readily accomplished by 85 means of any suitable switch.

When the subscriber's telephone at station No. 1 was included in circuit with the central office, as above explained, the beveled end of the switch-arm E became disposed under the 90 tooth or projection on the lever 7 when said switch-arm made contact with the screw F; but when the subscriber again hung his hand-phone on the hooked end of the switch-arm the latter was turned on its fulcrum, and the 95 beveled end thereof engaging the beveled projection on the end of the lever 7 forced the latter back against the resistance of the spring 8 and assumed its normal position above and out of contact with the projection 100 6 on lever 7.

Fig. 2 represents, theoretically, two party-lines connected together at the central office, so that a subscriber on one may converse with a subscriber on the other. A B and A' B' represent 105 two party-lines; 20 21, the resistances (corresponding with the resistance 3 shown in Fig. 1) to aid the locking devices, as above explained; 22, an annunciator for indicating to the operator at the central office when the 110 connection is no longer desired, and 23 represents the battery for operating the annunciator 22. The annunciator 22 is so constructed as to have a high self-inductive capacity 115 to prevent its short-circuiting the talking-circuit. It is obvious that if the annunciator 22 is not desired the conductors A and A' and B and B' may be simply connected together without the battery 23 or the resistances 20 21. There would then be no battery on either line 120 to operate the locking-magnets, and consequently no subscriber's telephone which was not already in circuit could be cut in and a conversation between two subscribers could not be interfered with or overheard by other 125 subscribers.

It will be understood that no special switch-board arrangements are necessary for applying our improvements with the exception of placing resistances in each line to aid the 130 hand-phones and transmitters in shunting the locking-magnets at the proper time. These

resistances may be placed outside the switch-board, if desired.

Other slight changes might be made in the details of construction of our invention without departing from the spirit thereof or limiting its scope, and hence we do not wish to limit ourselves to the precise details herein set forth.

Our improvements are simple in construction, can be easily applied and used in connection with any desired construction of switchboard, and are effective in all respects in the performance of their functions.

Having fully described our invention, what we claim as new, and desire to secure by Letters Patent, is—

1. In a telephone system, the combination with the line, a series of telephones thereon and lock-out devices for said telephones, of a normally open circuit for each telephone, a normally open circuit for each lock-out device of higher resistance than the telephone-circuit and a switch-arm common to both of said circuits, substantially as set forth.

2. In a telephone system, the combination with two line conductors, of a series of telephone apparatus arranged between said line conductors, each apparatus comprising a telephone and a lock-out device arranged in parallel between the line conductors, the circuit of the lock-out device being of greater resistance than the telephone-circuit and a switch-arm common to both circuits and constructed and arranged to maintain both of said circuits normally open, substantially as set forth.

3. In a telephone system, the combination with two line conductors and a source of electrical energy, of a series of telephone apparatus arranged between said line conductors, each apparatus comprising a telephone and a lock-out device arranged in parallel between the line conductors, the circuit of the lock-out device being of higher resistance than the telephone-circuit, a switch common to both circuits and arranged to maintain both normally open and a resistance included in the line-circuit, substantially as set forth.

4. In a telephone system, the combination with two line conductors and a source of electrical energy, of a series of telephone apparatus arranged between said line conductors, each apparatus comprising a telephone and a switch arranged in a normally open multiple-arc circuit and a lock-out device consisting of an electromagnet, a pivoted lever and said switch, said lock-out device being included in a circuit of higher resistance than the telephone-circuit and in parallel therewith, substantially as set forth.

5. In a telephone system, the combination with two line conductors and a source of electrical energy, of a series of telephone apparatus, arranged in parallel between said line conductors, each apparatus consisting of a switch-arm connected with one line conductor, a contact device to be engaged by said

switch-arm, a telephone connected in circuit with said contact device and the other line conductor, an electromagnet, a lever to be actuated by said electromagnet and normally disposed in the path of movement of said switch-arm, and a normally open multiple-arc circuit including said electromagnet, lever and switch, said last-mentioned circuit being of higher resistance than the multiple-arc telephone-circuit, substantially as set forth.

6. In a telephone system, the combination with two line conductors including in their circuit, a battery, an annunciator and a resistance, of a series of telephone apparatus arranged between said line conductors, each apparatus comprising a switch-arm pivotally supported between its ends and electrically connected with one of the line conductors, a normally open multiple-arc telephone-circuit including a telephone and a contact-screw and a multiple-arc circuit of higher resistance than said telephone-circuit including an electromagnet and a lever normally disposed in the path of one end of the switch-arm, substantially as set forth.

7. In a telephone system, the combination with two party-lines adapted to be connected together at the central office, each party-line comprising two line conductors, of a series of telephones arranged in parallel between the conductors of each line, lock-out devices for each telephone and included in circuits of higher resistance than the telephone-circuits, a resistance for each party-line and a "ring-off" annunciator and a battery arranged in multiple arc with both party-lines, substantially as set forth.

8. The combination in a telephone system, of two line conductors, a series of telephone apparatus arranged between said line conductors, each apparatus comprising a telephone and a lock-out device each arranged in parallel between said line conductors, a switch-arm common to both the telephone and the lock-out circuits and devices at the central office arranged to actuate said lock-out devices to control the movements of said switch-arm, substantially as set forth.

9. In a telephone apparatus, the combination with the line, of a telephone-circuit and a lock-out circuit, a magnet in the lock-out circuit, a pivoted switch-arm common to both of said circuits, a contact-point in the path of movement of one end of said switch-arm, a pivoted arm in the path of movement of the other end of said switch-arm, said pivoted arm being under the control of the magnet in the lock-out circuit, a bell, and devices intermediate of the switch-arm and the bell and coöperating therewith to sound the bell when the switch-arm engages the contact-point to close the telephone-circuit, substantially as set forth.

10. In a telephone apparatus, the combination with a switch-arm pivoted between its ends, a lock-out arm in the path of movement

of one end of said switch-arm, means for moving said lock-out arm, a contact-point in the line of movement of the other end of said switch-arm, a bell, and a bell-hammer fixed 5 to said switch-arm and adapted to strike the bell when said switch-arm engages said contact-point, substantially as set forth.

In testimony whereof we have signed this

specification in the presence of two subscribing witnesses.

ROBERT T. REID.
